UNITED STATES PATENT OFFICE.

HUGH O'DONNELL, OF LIVERPOOL, ENGLAND.

DESIGN FOR A MEDAL.

SPECIFICATION forming part of Design No. 28,965, dated July 5, 1898.

Application filed March 28, 1898. Serial No. 675,512. Term of patent 3½ years.

To all whom it may concern:

Be it known that I, HUGH O'DONNELL, hotel proprietor, a subject of the Queen of Great Britain and Ireland, residing at 24 Christian street, Liverpool, England, have invented a new and original Design for a Medal, of which the following is a specification.

In the annexed drawings, Figure 1 represents the obverse side, and Fig. 2 the reverse side, of a medal according to my novel design.

The design consists of a representation in profile of the head and shoulders of Lord Edward Fitz-Gerald, an Irish nobleman of the period A. D. 1798, wearing a tie-wig and military uniform with shoulder - epaulet surmounting a wreath of shamrocks arranged in a semicircle and tied in the center with rib-

bon, all in intaglio, upon the obverse side of a metallic medal, and the representation upon the reverse side thereof of an Irish wolf-dog, couchant, a harp having a broken string leaning upon an Irish cross, the latter being represented as falling, in the foreground a ruined tower, and house ruins in the middle distance, with the sea and sunrise or "sunburst" in the background, all in intaglio.

I claim—

The design for a medal substantially as herein shown and described.

In witness whereof I have hereunto set my hand in presence of two witnesses.

HUGH O'DONNELL.

Witnesses:

J. A. COUBROUGH,
J. W. MEIKLE.
